UNITED STATES PATENT OFFICE.

HARRY S. HART, OF CHICAGO, ILLINOIS.

SELECTIVE DUMP CAR.

Application filed April 22, 1924. Serial No. 708,144.

To all whom it may concern:

Be it known that I, HARRY S. HART, a citizen of the United States, residing at Chicago, in the county of Cook, and State of Illinois, have invented certain new and useful Improvements in Selective Dump Cars, of which the following is a specification.

The present invention relates to selective dump cars.

10 In railway dump cars, particularly those designed for the carrying of railway ballast, it is highly desirable to be able to dump either outside of the rails upon which the car is mounted or between said rails.

15 An object of the present invention is to provide a simple and rugged construction of railway dump car adapted for either side or center dumping.

20 A further object is to provide simple dumping mechanism which will deposit ballast adjacent to the rails of a railroad track with a minimum of danger of flooding said rails.

25 A further object is to provide a simple railway dump car of the selective type in which dumping may be efficiently accomplished while the car is traveling at a relatively high rate of speed without danger of flooding the rails.

30 A further object is to provide a railway dump car capable of carrying a relatively large load and having the advantage that dumping may be accomplished at a rapid rate without danger of rail flooding.

35 Further objects will appear as the description proceeds.

Figure 1 is a transverse sectional view of a railway dump car embodying the principles of the present invention, certain of the doors of said car being arranged for dumping outside of the tracks upon which the car is mounted; and

40 Figure 2 is a view taken along the same transverse plane as in Figure 1 but showing the doors arranged for center dumping.

45 The numeral 1 indicates a center sill, and the numerals 2—2 indicate cross bearers of a railway dump car. Said car is provided with the sloping walls 3—3, which extend 50 downwardly and inwardly from the sides

of the car. Disposed adjacent to the center sill 1 are the sloping walls 4—4, which slope downwardly and outwardly from the region of the center sill 1.

Hinged along longitudinal axes 5—5 adjacent to the walls 3—3 are the swinging doors 6—6, which swinging doors when in closed position extend in the same general directions as the corresponding sloping walls 3—3. Each of said swinging doors 6 is 55 adapted to form a hopper with the corresponding sloping walls 3 and 4, the two hoppers being arranged longitudinally of the car on the two sides of the center sill. Each of the floors 4—4 includes a swinging door 7 hinged about the longitudinally extending axis 8. Said doors 7—7 are so mounted that when said doors are in open position they will form practically continuous sliding surfaces with doors 6—6, assuming said doors 6—6 to be in closed position; this arrangement being clearly illustrated in Figure 2 of the drawing.

The swinging doors 7—7 are provided with members 9—9 projecting downwardly 75 from the under sides thereof, which members 9—9 provide attaching means for operating chains 10—10, which may be controlled in any preferred manner; shafts 11—11 being illustrated for this purpose. It will 80 be understood that the pulling up upon said chains 10—10 will move the swinging doors 7—7 to closed position. The swinging doors 6—6 are operated by means of chains 12—12, which may be controlled by the longitudinally extending shafts 13—13. In order to hold 85 chains 12—12 in proper positions to exert the necessary turning movement to the doors 6—6, sheaves 14—14 may be provided for carrying the operating chains 12—12. 90

Extending downwardly and outwardly from the lower edges of the sloping walls 4—4, that is—from regions adjacent to the longitudinally extending axes 8—8, are the sloping platforms 15—15. The lower edges 95 of said platforms 15—15 should be substantially straight and should project to regions laterally of the rails, for a purpose which will be referred to hereinafter. The edge portions of said platforms 15—15 may be 100

2
braced by any preferred means, as, for example, by the braces 16-16.

The wheels of the car are illustrated by the numerals 17-17, which wheels are adapted to ride upon the rails 18-18. As noted above, one of the objects of the present invention is to provide a structure by means of which ballast may be efficiently dumped either between the rails 18-18 or outside thereof without danger of flooding the rails. For this reason the doors 7-7 and the sloping platforms 15-15 are so designed that lading flowing therefrom will naturally assume such a position, due to its angle of repose, that flooding of the rails will be avoided.

It will be understood, of course, that the angle of repose of the lading will vary slightly with different kinds of lading and with varying degrees of wetness of said lading, but, speaking generally, the maximum dimensions of a heap of lading between the tracks may be defined by the broken lines indicated by the numeral 19 of Figure 2, which indicates the angle of repose of said lading. It will be noted that, given a predetermined angularity between the lines 19, the positions of said lines will be defined by the lower edges of the swinging doors 7-7 when said doors are in their full open position, as indicated in Figure 2; i. e., in alignment with their adjacent doors 6-6 when said doors 6-6 are in closed positions. It will be understood, of course, that there is a slight permissible variation in the base of the triangle representing the heap of lading between the rails. The base of said triangle may be at any level below the tops of the rails, so that said base is bounded by the inner surface of the rails below the tops thereof.

The lines defining the limits of heaps of lading outside of the rails are indicated by the numerals 20-20. Given a predetermined angularity of said lines 20-20 relative to a horizontal base, the positions of said lines are defined by the lower edges of the sloping platforms 15-15.

When it is desired to deposit lading between the rails, the doors 7-7 may be opened to permit the passage of lading to the region between said rails. Assuming that the doors 7-7 are swung to positions in alignment with the closed positions of the doors 6-6, the positions of the lines 19 indicating the top of the maximum permissible heap of lading will be defined by the lower edges of doors 7-7. By reason of the fact that the doors 7-7 direct lading to a medial region spaced equally from the rails 9-9, and inasmuch as the boundaries of the heap of lading are defined by said doors 7-7, the net result is that when the car is being moved along the track, at which time flooding of the rails is most

dangerous, the illustrated construction insures a maximum of safety in this regard.

The sloping platforms 15-15 will define the boundaries of the heaps of lading deposited outside of the rails, the delivery of lading to said platforms being controlled by doors 6-6.

It will be noted that according to the present invention a dump car is provided which combines the advantages of simplicity of operation, large carrying capacity, and minimum of likelihood of flooding the rails in service.

Though a preferred embodiment of the present invention has been described in detail, it will be clear that many modifications will occur to those skilled in the art. It is intended in this patent to cover all such modifications that fall within the scope of the invention as defined by the appended claims.

What is claimed is:—

1. A car of the class described having a center sill, a hopper portion on each side of the center sill, a platform extending downwardly and outwardly from the apex of each hopper portion, a downwardly swinging door hinged adjacent to the upper edge of the platform, and an outwardly swinging door hinged to the car frame above 95 said platform.

2. A dump car of the class described comprising a center sill, a pair of hopper portions arranged on two sides of said center sill, said hopper portions comprising sloping walls, the outer walls of said two hopper portions being provided with swinging doors having swinging edges mounted to swing adjacent to the bottoms of said hopper portions, said hopper portions having other swinging doors having their axes of swing arranged adjacent to the bottoms of said hopper portions, and relatively fixed sloping platforms extending downwardly and outwardly from the bottoms of said 110 hopper portions.

3. A dump car of the class described comprising a center sill and hopper portions arranged on the two sides of said center sill, said hopper portions being of V-shaped conformation, inwardly swinging doors pivoted along axes located adjacent to the bottoms of said hopper portions, outwardly swinging doors having their swinging edges adapted to swing into proximity to said bottom portions, and downwardly and outwardly sloping platforms for directing lading from the bottoms of said hopper portions to regions disposed laterally of said car.

4. A car of the class described comprising a pair of longitudinally extending hopper portions, each of said hopper portions being provided with doors which when in closed position are disposed in V-shaped relation 130

- to one another, one of said doors of each of said hoppers being pivoted at the base of said hopper and adapted to swing toward the longitudinal central plane of said car, 5 the other door of each of said hoppers being so mounted that its swinging edge when in closed position lies at the bottom of its corresponding hopper, each of said hopper portions being provided with a downwardly and outwardly sloping relatively fixed platform for directing lading laterally of the car.
5. A dump car of the class described comprising a pair of hopper portions arranged longitudinally of said car, each of said hopper portions being of V-shaped cross section, each of said hopper portions being provided with a swinging door hinged adjacent to the bottom of said hopper portion 10 for directing lading between the rails upon which the car is mounted, each of said hopper portions being provided with a sloping platform aligned with its corresponding swinging door when said door is in closed 15 position, and each of said hoppers being provided with another door for controlling the flow of lading to its adjacent platform, said platforms being disposed to direct lading outwardly of the tracks upon which said 20 car is mounted.
6. A dump car of the class described comprising a pair of hopper portions arranged longitudinally of said car, each of said hopper portions being of V-shaped cross section, each of said hopper portions being provided with a swinging door hinged adjacent to the bottom of said hopper portion 25 for directing lading between the rails upon which the car is mounted, each of said hopper portions being provided with a sloping platform aligned with its corresponding swinging door when said door is in closed 30 position, and each of said hoppers being provided with another door for controlling the flow of lading to its adjacent platform, said platforms being disposed to direct lading outwardly of the tracks upon which said car is mounted.
7. A dump car of the class described comprising a center sill, a pair of hopper portions arranged on two sides of said center sill, said hopper portions comprising sloping walls, the outer walls of said two hopper portions being provided with swinging doors having swinging edges mounted to swing adjacent to the bottoms of said hopper portions, said hopper portions having other swinging doors having their axes 35 of swing arranged adjacent to the bottoms of said hopper portions, and relatively fixed sloping platforms extending downwardly and outwardly from the bottoms of said hopper portions, said first mentioned swinging doors and said platforms having discharge edges located at regions coinciding with lines indicating the angle of repose of railway ballast, which lines extend through vertical planes of said rails below the tops 40 of said rails.
8. A dump car of the class described comprising a center sill and hopper portions arranged on the two sides of said center sill, said hopper portions being of V-shaped conformation, inwardly swinging doors pivoted along axes located adjacent to the bottoms of said hopper portions, outwardly swinging doors having their swinging edges adapted to swing into proximity to said bottom portions, and downwardly and outwardly sloping platforms for directing lading from the bottoms of said hopper portions to regions disposed laterally of said car, said first mentioned swinging doors and said platforms having discharge edges located at regions coinciding with lines indicating the angle of repose of railway ballast, which lines extend through vertical planes of said rails below the tops 45 of said rails.
9. A dump car of the class described comprising a pair of hopper portions arranged longitudinally of said car, each of said hopper portions being of V-shaped cross section, each of said hopper portions being provided with a swinging door hinged adjacent to the bottom of said hopper portion 50 for directing lading between the rails upon which the car is mounted, each of said hopper portions being provided with a sloping platform aligned with its corresponding swinging door when said door is in closed position, and each of said hoppers being provided with another door for controlling the flow of lading to its adjacent platform, said platforms being disposed to direct lading outwardly of the tracks upon which said car is mounted, said first mentioned swinging doors and said platforms having discharge edges located at regions coinciding with lines indicating the angle of repose of railway ballast, which lines extend through vertical planes of said rails below the tops 55 of said rails.
10. A railway dump car of the class described comprising a pair of hopper portions extending longitudinally of said car, said hopper portions having adjacent swinging doors adapted to permit the passage of lading between the tracks upon which said car is mounted, said hopper portions also being provided with relatively fixed downwardly and outwardly sloping platforms for directing lading laterally of said tracks,

each of said hoppers being provided with another swinging door for controlling the passage of lading to said platforms, said first mentioned swinging doors and said platforms having their discharge edges arranged when in dumping position to coincide with lines indicating the angle of re- pose of ballast, which lines pass through the planes of said rails at regions below the tops of said rails.

Signed at Chicago, Illinois, this 17th day of April, 1924.
